UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

SHIRRING PRESSER-FOOT FOR SEWING-MACHINES.

1,144,228.

Specification of Letters Patent. Patented June 22, 1915.

Application filed November 18, 1908. Serial No. 463,227.

To all whom it may concern:

Be it known that I, JAMES R. MOFFATT, a citizen of the United States, residing at Chicago, in the county of Cook, State of Illinois, have invented certain new and useful Improvements in Shirring Presser-Foots for Sewing-Machines, of which the following is a description, reference being had to the accompanying drawings and to the letters and figures of reference marked thereon.

My invention relates to new and useful improvements in shirring machines.

The object of my invention is to provide a sewing machine in which a strip of fabric may be shirred and at the same time provided with a heading.

The invention is more especially adapted for shirring a strip and securing the same to the flounce or body of a skirt, and at the same time, forming a covering or binding to the overlapped raw edges of the two fabrics, whereby said strip is shirred and secured to the body of the skirt, and a heading formed, in a single operation.

The invention consists in the matters hereinafter described and referred to in the appended claims.

The invention is illustrated in the accompanying drawings, in which:

Figure 1 is an end view partly in section, and with parts broken away showing a sewing machine with my improvements applied thereto. Fig. 2 is a top plan view of the main and auxiliary presser feet. Fig. 3 is a bottom plan view of the same. Fig. 4 is a rear view of the same. Fig. 5 is a plan view representing the work done on this machine. Fig. 6 is a top plan view of the presser foot, showing the guides for guiding the strip to be shirred, and the body fabric. Fig. 7 is an end view of the presser foot detached. Fig. 8 is a section through the fabrics showing the shirred strip and the heading therefor. Fig. 9 is a sectional view through the presser foot, showing the means for adjusting the section of the foot which forms the shirring.

The presser foot and guide may be used in connection with a sewing machine of any desired type; but for the sake of illustration, I have shown it applied to a multiple needle single chain stitch machine, in which the needle bar 1 reciprocates in the usual manner in the head of the machine, and carries a needle 2.

The presser bar 3 is also mounted in the usual manner, in the head of the machine, and is lifted by the usual hand lever 4. At the lower end of the presser bar 3 is a presser foot 5. Coöoperating with the presser foot 5 is a dog 6 carried by the feed bar 7, which is of the usual four motion feed type, and is operated in any suitable way. A looper 8 coöperates with the needle 2.

The main presser foot 5 is formed with a main section which is attached to the presser bar and which is so constructed as to cause the fabric engaged thereby to be shirred. This section of the foot is formed with a recess on its under face in which is placed a part 18. The part 18 is carried by a post 29 which extends up through a collar 31^a carried in the shank of the presser foot and a pin 30 passes through an opening in the post and is mounted in said shank. This opening in the post is slightly larger than the diameter of the pin, which permits of certain limited adjustment of the post in the collar. A screw 31 engages the post and rests on the upper end of the collar 31^a. Said screw is provided with a groove 32 which engages a fixed part on the shank, and which prevents endwise movement of the screw. By adjusting the screw 31, the plate or part 18 may be adjusted toward and from the lower face of the presser foot. If this part is so adjusted as to be flush with the lower face of the presser foot, no shirring action will occur. When, however, it is adjusted so as to form a space or recess in rear of the part of the presser foot through which the needle extends, then the fabric as it is being stitched will pile up or be gathered at the point of stitching. This occurs by reason of the fact that the feed dog 95 coöperating with the presser foot clamps and feeds the fabric in advance of the needle slightly faster than in rear of the needle. This particular form of shirring presser foot *per se* forms no part of my present invention, but is shown, described and claimed in the application of R. G. Woodward, filed May 5th, 1908, Serial No. 430,899.

The presser foot 5, in addition to the section which is provided with means for shirring the fabric, is also provided with an auxiliary foot *c* which is adapted to engage a heading which is to be stitched to the shirred fabric.

While I have shown the above described

BEST AVAILABLE COPY

construction of presser foot for shirring the fabric, it will be understood that other forms of shirring means may be used in place of the one herein illustrated, as the essential feature of the present invention is broadly some means for shirring the fabric at the same time that the shirred strip is provided with a heading. The auxiliary foot *c* is provided with a post *b* which extends up through a suitable opening in a block *a*, secured to the presser foot 5 in any suitable way.

The block *a* is provided with a plate *f* which is secured thereto by suitable screws *e*. The plate *f* has a rearwardly projecting lug *g*. A spring *i* encircles a headed screw *h* threaded in the lug *g*, and is supported thereby. Said spring extends upwardly through a recess in the rear side of the block *a* and is then coiled and extends laterally so as to rest upon the top of the post *b*. A screw *k* threaded through the plate *f*, bears against the upwardly extending shank of the spring *i*, and serves as a means whereby the tension of the spring *i* on the post *b* may be varied.

The post *b* is also provided with a pin *b'* which serves to limit the downward movement of said post when the presser bar is lifted. The auxiliary foot *c* is located close to the main foot 5, and is provided with two needle holes as herein shown. A tape guide *d* is carried by the auxiliary foot *c* and has an opening leading down through the foot. On the under side, the auxiliary foot *c* is provided with a recess *c'*, which is substantially the width of the tape passing from the tape guide and extends to the rear edge of the auxiliary foot, thus forming a guiding recess for the tape.

As above noted, my invention is especially adapted for shirring a strip such as *S* and stitching the same to a body fabric such as *B*, and covering the edges of the body fabric and shirred strip by means of a strip or tape *T* all of which is clearly shown in Figs. 5 and 8. As a means for guiding a body fabric and folding the edge thereof, I have provided an edge guide 20 which is pivoted at 21 to a plate 22, adjustably attached to the work plate of the machine, by screws 23.

The edge guide 20 is provided with a folder 24 so that as the body fabric passes through the guide, the edge thereof will be folded back upon itself as clearly shown in Fig. 8. Mounted on the guide for the body fabric, is an edge guide 25 for the strip to be shirred. Said guide 25 is adjustably secured to the guide 20 by means of a screw 26, and is provided at its forward end with a backwardly turned lip 27 forming a guiding recess for the strip to be shirred.

It is noted that the guide for the shirring strip is so located that the edge of the strip being shirred is also led underneath the auxiliary presser foot *c* and between the needle

slots therein so that when the tape is stitched at its edges, to the body fabric and the shirred strip, the edge of said shirred strip is underneath said tape.

The guide for the body fabric and the guide for the shirred strip can of course, be adjusted so as to secure the fabrics together in any desired relation.

Having thus particularly described my invention, what I claim as new and desire to secure by Letters Patent is:

1. A sewing machine for shirring a fabric and forming a heading thereon, including in combination a plurality of needles a main presser foot, means carried thereon whereby the fabric is shirred, and an auxiliary presser foot arranged at one side of the main presser foot, and acting on the heading.

2. A sewing machine for shirring a fabric, and forming a heading thereon, including in combination a plurality of needles a main presser foot, means carried thereon whereby the fabric is shirred, an auxiliary presser foot arranged at one side of the main presser foot and acting on the heading, and a double edge folder carried by said auxiliary presser foot for folding and guiding a tape to form the heading.

3. A sewing machine for shirring a fabric and forming a heading thereon including in combination a main presser foot, means carried thereon whereby the fabric is shirred, an auxiliary presser foot arranged at one side of the main presser foot and acting on the heading and a double edge folder carried by said auxiliary presser foot for folding and guiding a tape to form the heading, said presser having a recess on its inner face to receive and guide said folded tape after it is stitched.

4. A sewing machine including in combination, a plurality of needles arranged side by side, a main presser foot engaging the fabric operated upon by certain of said needles, means cooperating with the fabric engaging face of said main presser foot in rear of the needle for forming shirring in said fabric, an auxiliary presser foot at one side of said main foot having means for guiding a heading.

5. A sewing machine including in combination, a main presser foot, and means for forming a heading on the material being sewed including an auxiliary presser foot engaging said heading, said main presser foot having a bearing surface in advance of the needle and a recess or cut away portion in rear of the needle.

6. A sewing machine including in combination, a main presser foot, and means for forming a heading on the material being sewed including an auxiliary presser foot engaging said heading, said main presser foot having a bearing surface in advance of the

- needle and a recess or cut away portion in rear of the needle, and means for yieldingly supporting said auxiliary presser foot, whereby the same may yield vertically to accommodate overlapping folds in the material.
7. A sewing machine including in combination, a plurality of needles arranged side by side, a main presser foot having means for forming shirring, means for forming a heading including an auxiliary presser foot at one side of said main foot for guiding said heading so as to cover one edge of the shirring.
- 10 8. A sewing machine including in combination a plurality of needles, a main presser foot having a portion arranged to engage the fabric in advance of the needles only, an auxiliary presser foot extending in front 20 and in rear of said needles, and located at one side of said main foot, and means for guiding a heading to said auxiliary presser foot.
9. A sewing machine including in combination, a plurality of needles, a main presser foot having a bearing surface acting on the fabric in advance of said needles and terminating on a line with said needles and an auxiliary presser foot arranged in front of 25 and behind said needles and at one side of said main presser foot.
10. A sewing machine including in combination a plurality of needles, a main presser foot having a bearing surface acting on the fabric in advance of said needles, and terminating on a line with said needles, and an auxiliary presser foot arranged in front of and behind said needles, and at one side 30 of said main presser foot, and means where-
- by one of said presser feet can be adjusted vertically irrespective of the other.
11. The combination of a main shirring presser foot, having a relatively fixed portion and an adjustable portion in rear of said relatively fixed portion and a tape guiding presser foot located at one side of said main presser foot and supported thereby.
12. The combination of a main shirring presser foot, having a relatively fixed portion, an adjustable portion in rear thereof, 50 a block carried by said main presser foot, an auxiliary presser foot carrying a tape guide yieldingly supported by said block.
13. A sewing machine including in combination a main presser foot having means for shirring a fabric, an auxiliary presser foot, a doubled edge folder carried by said auxiliary presser foot and a second folding device arranged to deliver its fold underneath the fold of the top folder.
14. A sewing machine for shirring and heading a fabric including a main presser foot having means for shirring said fabric, an auxiliary presser foot, a double edge folder carried by said auxiliary presser foot, a folding guide arranged to direct a folded fabric underneath said auxiliary presser foot and an edge guide for guiding the strip to be shirred so that its edge is led underneath said auxiliary presser foot, whereby 60 said edge is inclosed between the two folded strips.
- In testimony whereof I affix my signature, in presence of two witnesses.
- JAMES R. MOFFATT.
